(57) **CLAIM**

The ornamental design for a blow dryer, as shown and described.

DESCRIPTION

FIG. 1 is a top, right side perspective view of a new, original and ornamental design for a blow dryer;

FIG. 2 is a right side elevation view of FIG. 1;

FIG. 3 is a left side elevation view of FIG. 1;

FIG. 4 is a front elevation of FIG. 1;

FIG. 5 is a rear elevation view of FIG. 1;

FIG. 6 is a top plan view of FIG. 1; and,

FIG. 7 is a bottom plan view of FIG. 1.

The broken lines in the drawings depict portions of the blow dryer that form no part of the claimed design.

1 Claim, 5 Drawing Sheets
